PANTOGRAPH

Stanislaw Feld, New York, N. Y.

Application May 8, 1944, Serial No. 534,577

1 Claim. (Cl. 33—25)

1

The object of my invention is to provide an adjustable pantograph wherein the several bars are pivotally connected by means which may be considered permanent and unnecessary to be disturbed for proportioned adjustment, and means for insuring accurate adjustment of the stylus and marker elements by the setting of a single set of graduations.

The accompanying drawing illustrates my invention, in which

Fig. 1 is a perspective view of an embodiment of my invention in position upon a working surface;

Fig. 2 is a plan with the parts in position for adjustment;

Fig. 3 is a perspective view of the stylus or scribe carrier;

Fig. 4 is an axial section of the main carrier head; and

Fig. 5 is a fragmental elevation of a detail.

In the drawing 10 indicates a main carrier provided at one end with clamping means 11 by means of which the carrier 10 may be rigidly held in position over the work surface, and provided at the other end with a rotary turret 12 journaled by the trunnion 13 on the base block 14 secured to the carrier 10. Turret 12 is provided with a diametrical perforation 15 in which the main bar 16 of the pantograph is slidably mounted, said main bar being provided with a series of graduations 17 to indicate the proportional setting of the apparatus. Bar 16 may be held in any desired position of adjustment relative to turret 12 by the set screw 18. Pivoted at one end of bar 16, at 19, is one end of a stylus bar or scribe bar 20. Pivoted at 21 to the opposite end of main bar 16 is the middle of a stylus bar or scribe bar 22. Pivoted at 23 at one end of bar 22 is one end of a control bar 24, the opposite end of which is pivoted, at 25, to the middle of bar 20, the distance between pivots 19 and 25 being equal to the distance between pivots 21 and 23. Slidably mounted on the free ends of bars 20 and 22 are carriers 26, 26, each of which may be held in its adjusted position by its thumb screw 26'. Either carrier 26 may be considered as the stylus, and the other as the scribe.

The main bar 16 may be adjusted lengthwise through the turret 12. When in its middle position, where the distance between the axis of the turret 12 and pivot 21 is equal to the distance between pivots 19 and 25 and between pivots 21 and 23, the figure produced by the scribe will be the same size as the figure traced by the stylus. Adjustment of bar 16 from this middle position

2

in one direction, will cause the scribe to produce figures larger than the figure traced by the stylus, while adjustment in the opposite direction will cause the scribe to produce figures smaller than the figures traced by the stylus.

In order to facilitate accurate adjustment of the stylus and scribe carriers without the need of adjustment scales on the bars 20 and 22, I provide turret 12 at diametrically opposite points, 10 with pockets 27, 27 and provide each carrier 26 with a finger 28 adapted to fit the adjacent pocket 27.

In order to adjust the apparatus to a desired proportion, thumb screws 26', 26' are loosened, 15 the several bars collapsed to the position shown in Fig. 2, and fingers 28, 28 seated in the pockets 27, 27. Thumb screw 18 being loosened, main bar 16 may be shifted through turret 12 to the desired position, as indicated by the graduated scale 17 and then fastened in position by thumb screw 18. During this operation, the two carriers 26 will be automatically shifted to proper positions for the desired proportionate setting, and the thumb screws 26' may then be tightened.

20 It will be noted that the operation of adjustment may be performed by a single operation and that the pivotal connections 19, 21, 23 and 25, between the several bars of the pantograph, need not be disturbed. These pivotal connections, 30 therefore, may be of a permanent, non-separable character thus contributing materially to continued accuracy of operation and also avoiding any possibility of loss or displacement of the parts. It will be noted that during the operation of shifting of the main bar 16 with the two carriers 26 interlocked with the turret 12, one of the carriers will be moved toward the pivotal support of its carrying bar while the other of said carriers will be proportionately moved away from the pivotal supports of its carrying bar.

40 I call attention to the fact that either carrier 26 may carry the stylus while the other carries the scribe but, for convenience in the claim, bar 20 will be designated the stylus bar and bar 22 will be designated the scribe bar, but in interpreting the claim it is to be understood that the terms "scribe" and "stylus" may be interchanged.

I claim as my invention:

50 A pantograph comprising a main bar, a pivotal support for the main bar with respect to which the main bar is slidably transversely of said pivot, a stylus bar pivotally associated with one end of said main bar, a scribe bar pivotally associated 55 with the other end of said main bar, a controller

bar pivotally connected to the scribe bar and the stylus bar so as to maintain parallel relationship with the main bar, a stylus carrier slidably mounted upon the free end of the stylus bar, a scribe carrier slidably mounted on the free end of the scribe bar, means to hold said scribe carrier and stylus carrier in adjusted position, and

5 mating means carried respectively by the main bar support and the stylus and scribe carriers for holding the stylus carrier and scribe carrier in fixed relation relative to the main bar support during shifting of said main bar transversely of the pivot of said support.

STANISLAW FELD.
